CIRCULAR KNITTING MACHINE

Paul L. Thurston and Harrison F. Hilker, Martinsburg, W. Va., assignors to Interwoven Stocking Company, New Brunswick, N. J., a corporation of New Jersey

Application February 17, 1940, Serial No. 319,454

18 Claims. (Cl. 66—9)

Our invention consists in the novel features hereinafter described, reference being had to the accompanying drawings which illustrate one form of circular knitting machine embodying our invention, selected by us for purposes of illustration, and said invention is fully disclosed in the following description and claims.

Our invention consists in a circular knitting machine for producing by reciprocating knitting, a straight non-tubular piece of plain knit fabric, having a continuous elastic thread incorporated therein in certain preferably spaced courses, and united to the fabric at spaced wales in said courses and floated on the inner face of the fabric across an intervening wale, or intervening wales, so as to form horizontally extending beads on the inner face of the fabric, the said piece of circular knit non-tubular fabric being of such width, and having such number of stitches in the courses thereof as to permit it to be united, 10 stitch for stitch to the upper end of the leg portion of a flat knit or full-fashioned sock, anklet or stocking, and to form a self-supporting top therefor, by transferring it to a straight or full-fashioned knitting machine, or by looping or 15 sewing it to the leg portion produced thereby, or otherwise, the ends of the said circular knit non-tubular fabric being united by a continuation of the seam connecting the marginal edges of the full-fashioned foot and leg of the stocking.

The process of knitting a stocking top of this construction, and combining it with a full-fashioned leg and foot, as well as the stocking top, and the sock, anklet or stocking, so produced, are disclosed in and covered by the claims of our former application for Letters Patent of the United States, filed by us October 5, 1939, and given Serial No. 297,970, and these subjects matter are not claimed herein. It will be understood that the horizontal beads formed on the inner 20 face of the straight, non-tubular, circular knit top by the floated portions of the elastic thread will indent the skin of the wearer and interlock therewith so as to support the top and the leg of the sock, anklet or stocking upon the leg, and dispense with all necessity for garters or other extraneous supporting means.

As is well-known, full-fashioned hosiery is formed as a flat fabric on a machine capable of simultaneously producing an entire course of 25 stitches, of varying lengths to facilitate the fashioning of the stocking, sock or anklet, and this flat fabric is subsequently folded on a vertical central line, and the edges are united by a seam extending vertically down the back of the leg, 30

and along the bottom of the foot portion to complete the article. These machines are very complicated and very expensive, and operative at comparatively slow speed. It has been proposed to introduce elastic thread into the top of a full-fashioned sock, or anklet, for garter purposes, but this involves material changes in and additions to the already extremely complicated knitting machines, increasing the expense thereof, and the introduction of an elastic thread in the operation of such machines further slows down their operation so that the output per day is comparatively small.

According to our invention we form the form-fitting and self-supporting top for a full-fashioned leg and foot by knitting the top of plain knitting with incorporated elastic thread, preferably in the manner hereinafter described, on a simple circular plain knitting machine of the kind provided with a circular series of independently operable needles and operating cam mechanism and means for establishing relative rotation between the needle cylinder and cam mechanism for the production of a knitted tube. These machines are very simple in construction, can be made very cheaply, and can be operated at extremely high speeds. We prefer to use a circular plain knitting machine of this type, which is not complicated by any narrowing and widening mechanism or other foot forming means, although obviously, our invention could be carried out on any machine capable of making a tubular plain knit fabric.

In carrying out our invention, we select a 35 circular plain knitting machine having a greater number of needles than a single section of the full-fashioned knitting machine which is to knit the full-fashioned leg and foot of the stocking, sock or anklet, and remove therefrom a group of consecutive needles of the circular series of needles so as to leave a number of needles equal to the number of needles of the full-fashioned machine section, in order to knit the top as a non-circular plain knit fabric having vertical selvages at its opposite lateral edges, and to facilitate the attachment of said top to the full-fashioned leg by transferring the top to the needles of the full-fashioned knitting machine, or by looping, sewing or otherwise. The circular knitting machine is then operated in the formation of the top by reciprocating circular movement in conjunction with means for feeding a body thread to all the remaining needles in every course, and an elastic thread in selected 40 and preferably spaced courses in which it is fed

to selected, and preferably spaced needles, in any one of the known ways in which an elastic thread may be incorporated in a plain knit fabric, so as to provide a series of horizontal floats on the inner face of the fabric to indent the skin of the wearer and support the stocking on the leg. This produces what we term in the following description and claims, a plain knit circular knit form-fitting and self-supporting flat top for a full-fashioned stocking, preferably having a transfer course of stitches equal in number to the number of needles of one section of a full-fashioned knitting machine, and which can therefore be straightened out into a single plane, transferred to the needles of a full-fashioned machine to knit the leg and foot integrally therewith, the stocking being completed by seaming together the lateral selvages of the flat knit foot and leg and the lateral selvages of the top to form a complete full-fashioned stocking, sock or ankle, or as above indicated, the leg and foot may be knit separately on a full-fashioned machine, and the circular knit top may be applied thereto by looping, stitching, or in any other desired manner.

As the top is knit by reciprocating work on the circular knitting machine, the introduction of the elastic thread will obviously take place first in one direction and then in the other direction in immediately succeeding courses in which it is incorporated, thereby producing adjacent to the lateral edges or selvages of the top, vertical floats where the elastic thread is carried from one course to the succeeding course in which it is incorporated. It is particularly desirable to make this top by reciprocating work on the circular knitting machine in order to provide vertical selvages at each lateral edge of the top, and also to avoid cutting the elastic thread which is fed under appreciable tension. In this manner of knitting, the elastic thread is continuous throughout the top and the individual portions in each course will retain the tension under which the elastic thread was fed.

It is known that an elastic thread may be incorporated in knitted fabrics in a number of ways, including the following:

1. By laying-in (as it is termed in the art) the elastic thread, by feeding it to the selected and preferably spaced needles, so that it lies below the latches thereof prior to the drawing of a stitch of body thread thereby in which case the elastic thread does not form part of any stitch, but is united to the fabric by the encirclement of the sinker wales on opposite sides of the stitches formed by the selected needles.

2. By feeding the elastic thread to selected needles in plating relation with the body thread so that the stitches drawn by such selected needles will contain both the body thread and the elastic thread.

3. By feeding the elastic thread to the hooks of selected needles which draw a stitch of the elastic thread through the previously formed stitch of body thread which is cast off.

Our invention may be carried out in any one of these ways, but for purposes of illustration, we have herein described the incorporation of the elastic thread by the first mentioned method, to wit, the "laying-in" of the elastic thread, so that it is not knit, but is held by the sinker wales on opposite sides of the stitches formed by the selected needles. In the formation of the circular knit top, we prefer to provide it with a preliminary anti-ravel course of stitches at its up-

per edge through all of which the elastic thread extends, preferably by feeding the elastic thread to every other of the needles which are temporarily raised above the intervening needles, 5 then raising the intervening needles to the same level as the selected needles and subsequently raising all the needles to bring the elastic thread below the latches of the selected needles and subsequently feeding the body thread to the 10 hooks of all the needles which then draw loops of the body thread on opposite sides of the elastic thread to form the anti-ravel course. This involves a 1 x 1 needle selection for the anti-ravel course. We prefer to provide in the subsequent courses, and preferably beginning with the second course of the top, for a wider needle selection which may be a separation of two, three, four or other number of needles between the selected needles, as may be found most advantageous.

We also prefer to introduce the elastic thread in spaced courses, as it is more expensive than the ordinary body thread, but on account of the reciprocations of the machine, it can only be introduced either in a course following the preceding course containing it, or a course separated therefrom in which the travel of the reciprocating cylinder will be in the proper direction that is to say, the first, third, fifth or seventh, and so 25 forth, course following a preceding course containing it. In this instance we have shown the elastic thread incorporated in the second course, immediately after the formation of the anti-ravel edge, and thereafter in every third course, 30 uniformly through the fabric, although it is not essential that the separation of the elastic thread bearing courses should be uniform throughout the top and any desired arrangement is within the scope of our invention. We wish 35 to be understood, however, that the formation of the anti-ravel course may be omitted, and the anti-ravel effect produced by turning over a welt and stitching it, or by the formation of any other type of anti-ravel edge.

40 In the accompanying drawings in which we have shown one form of circular knitting machine embodying our invention—

Fig. 1 is a front elevation of a circular knitting machine embodying our present invention.

Fig. 2 is a right side elevation of the machine.

Fig. 3 is a left side elevation of the machine.

Fig. 4 is a top plan view of the machine.

Fig. 5 is a horizontal sectional view of the machine taken on the line 5—5 of Fig. 1.

Fig. 6 is a horizontal sectional view of the machine taken on the line 6—6 in Fig. 1.

Fig. 7 is a diagrammatic exterior view of the cylinder and cams of the knitting machine as they would appear if cut vertically at one point 60 and spread out in a single plane, and illustrating the rotary movement of the cylinder in a clockwise direction.

Fig. 8 is a similar diagrammatic view, with the cylinder cut at a different point and indicating the position of the parts during the movement of the cylinder in either direction after all the needles have received their thread or threads.

Fig. 9 is a view similar to Fig. 7 showing the cylinder cut at a slightly different point, and illustrating the movement of the cylinder in a counter-clock-wise direction opposite to that indicated in Fig. 7.

Fig. 10 is an enlarged detail partial sectional view illustrating the needle cylinder, the needles, jacks and cams, and illustrating the relations of

the parts in effecting the desired needle selection for producing the anti-ravel edge.

Fig. 11 is a similar view showing the parts in the positions which they occupy during the knitting of intermediate courses between the selected courses in which the elastic thread is incorporated.

Fig. 12 is a similar view showing the parts in the positions which they occupy to effect a needle separation in the courses of the top in which the elastic thread is incorporated.

Fig. 13 is a diagrammatic view of the inner face of the circular knit rubber incorporated top for full-fashioned hosiery provided with a course of enlarged transfer stitches and ravel courses, for facilitating the transfer of the top to a straight knitting machine.

Fig. 14 is a plan view of a full-fashioned sock or anklet having the circular knit top united to the upper end of the leg thereof.

Fig. 15 is a perspective view of a completed sock or anklet having a full-fashioned foot and leg, and the circular knit rubber incorporated self-supporting top.

In carrying out our present invention, we employ a circular knitting machine capable of producing plain knitting and provided with a circular series of independently operable needles greater in number than the number of needles in one section of the straight knitting machine which is to knit the leg portion of the sock, anklet or stocking, below and immediately following the top, so that a certain number of consecutive needles may be removed from the grooves of the needle cylinder, to form a gap, and leave in the needle grooves exactly the same number of consecutive needles as are present in the straight knitting machine sections. This facilitates the union of the top with the leg portion, stitch for stitch, by transferring, looping or otherwise, and preferably by transferring a series of transfer loops adjacent to the lower edge of the top to needles of the straight knitting machine and knitting the leg portion integral with the top.

We prefer to employ for the knitting of the top a circular knitting machine not provided with narrowing and widening mechanism, as such machines are simpler and cheaper, and the narrowing and widening mechanism is not needed for carrying out our invention. It will be understood, however, that our invention may be embodied in any circular knitting machine capable of producing plain knitting on a single circular series of needles by reciprocating work.

In the machine illustrated in the drawings, 1 represents the needle cylinder which is provided with means (not shown) for driving it first in one direction substantially two and one quarter revolutions, and then in the other direction to the same extent. A certain number of the independently operable needles have been removed from the cylinder leaving a gap, which is indicated at G in Figs. 5, 7, 8 and 9. In Figs. 7, 8 and 9, this gap appears in different locations in accordance with the different positions of the cylinder rotarily with respect to the cam mechanism illustrated in these figures. The needles which are indicated at n and n', n2, in Figs. 10, 11 and 12, are provided with the usual knitting butts 3, and with selecting jacks 2, and these jacks are provided with selecting butts of different length, the jacks for certain needles being provided with short butts 4, and those for other needles being provided with long butts 4a.

The cam mechanisms for operating the needles

are shown diagrammatically in Figs. 7, 8 and 9, and are supported by the usual cam block and cam ring 20.

Means is provided for establishing reciprocating relative rotary movement between the needle cylinder and the cam mechanisms. In the embodiment illustrated, the cam ring is stationary while the cylinder is rotated first in one direction approximately two and one quarter revolutions and then in the other direction to the same extent by mechanism comprising a gear segment 201 carried by a pivoted bell crank 201a which is connected by a link 202 with a crank pin 203 on a gear wheel 105 driven by a gear 106 on main drive shaft 107. The gear segment 201 meshes with a gear 204 which is freely rotatable on shaft 107 and which drives the needle cylinder through suitable bevel gearing. The main knitting cam is indicated at 5, and auxiliary cams 6 and 7 respectively, are arranged on opposite sides of cam 5, each of these auxiliary cams being movable into and out of operation, preferably radially with respect to the cylinder, one of the auxiliary knitting cams being moved into operative position when the cylinder is rotated in one direction and the other being brought into operation when the cylinder is rotated in the opposite direction, while the first mentioned auxiliary cam is withdrawn, and at certain times both auxiliary cams are withdrawn as indicated in Fig. 8 for example, in which both of said cams are shown in dotted lines, and as hereinafter described.

On opposite sides of the auxiliary cams 6 and 7 are arranged riser cams 9 and 11 respectively, the said cams being provided with cut away portions 9a and 11a respectively, in horizontal alignment, with the auxiliary cams 6 and 7. These cut away portions permit the knitting butts 3 of the needles to pass one or other of the riser cams according to the direction of rotation of the cylinder when the auxiliary cam adjacent thereto is in operative position as shown in Fig. 7. Adjacent to each of the auxiliary cams 6 and 7, there is provided a stationary riser cam 8 (or 10) extending in the opposite direction from the adjacent riser cam 9 (or 11), the stationary riser cams 8, and 10 being conveniently formed on the cam ring 20.

There are also provided on opposite sides of the main knitting cam mechanism the shunt cams 12 and 13 respectively, which are located in the horizontal plane of the cutaway portions of cams 9 and 11, and independently movable into and out of position, according to the direction of rotation of the cylinder for shunting the knitting butts of the needles upward into engagement with either cam 9 or 11 as the case may be, as shown in Figs. 7 and 9. The shunt cams 12 and 13 may both be withdrawn at the same time from operative position to enable the needle butts to pass horizontally through the cutaway portions of cams 9 and 11, when desired, as shown in Fig. 8.

In this instance we prefer to provide the cam ring on the side opposite from the main knitting cam mechanism just described, with a secondary conditioning cam mechanism comprising a central cam 5a, auxiliary cams 6a and 7a, on opposite sides of cam 5a, and cooperating with riser cams 8a and 10a, all of which are stationarily supported by the cam ring, and secondary cam block.

In addition to the conditioning cam mechanism previously described, and cooperating therewith, the machine is provided with two jack selecting

cams 14 and 15 located below and on opposite sides of a vertical line passing through the secondary knitting cam 5a, and engaging the butts of the selecting jacks as hereinafter described, said selecting cams being movable into and out of operative position radially of the cam ring or block, and operated by pattern controlled mechanism, hereinafter described, so that both selecting cams may be out of operative position simultaneously, and so that one or other of said selecting cams may be moved into position to engage the long butts of the jacks, or the long and short butts of the jacks, as required, and in accordance with the direction in which the cylinder is being rotated.

16 represents the thread feed finger for the body thread B, and 17 represents the thread feed finger for the elastic thread E, located on the opposite side of the cylinder from the feed finger 16, which will be a thread of rubber, or a thread composed of rubber and fibrous material such as that known under the registered trade-mark "Lastex" or any other kind of elastic thread which will accomplish the result desired.

I also prefer to locate a latch opener 18 in front of the feed finger 17, and a second latch opener 19 in front of the thread feed finger 16 to insure all the latches of the bare needles being opened to receive the respective threads E and B, when beginning the first course of the top.

In the formation of the circular plain knit top embodying our invention, we prefer to start up on bare needles, and as before stated, to provide in the first course of the top, an anti-ravel, and it will be thus described. Assuming that the cylinder is rotated in a clock-wise direction as indicated by the arrow, in Fig. 7, the shunt cam 13, auxiliary knitting cam 7, and selecting cam 15, will be drawn out into inoperative position, as indicated by the dotted lines in Fig. 7, while the shunt cam 12 and auxiliary knitting cam 6 will be pushed in, into operative position. The selecting cam 14 will also be pushed inwardly into its innermost position, to engage all the butts of the needle jacks which will thus raise every other needle, since the jacks for the intermediate needles have been removed. The feeding of elastic thread will always precede the formation of stitches of body thread and the first needles to receive the elastic thread will be those at the right of the gap G, as indicated at x in Fig. 7, which represents the cylinder after the first revolution of the cylinder is nearly completed.

As the portion of the cylinder indicated at x approaches the feed finger 17, for the elastic thread, a needle separation is effected in the following manner. The jack cam 14 will engage both the short butts 4 and long butts 4a of the jacks, which are provided for the alternate needles only, and raise every other needle into position to be engaged by the latch opener 18 (see Fig. 7), which insures the opening of the latches of the raised alternate needles, to receive the elastic thread E in their hooks, while the needles not provided with jacks are drawn downward by the engagement of their knitting butts 3, with the cam 1a of the conditioning mechanism (see Fig. 7), thus producing an effective separation between the raised and lowered needles. The raised needles, together with their jacks, are drawn down by the engagement of their knitting butts 3, with the cam 5a of the conditioning cam mechanism and take the elastic thread E in their hooks, and are drawn down fur-

ther by the cam 6a of the conditioning cam mechanism, so as to carry the elastic thread inside of the intermediate needles, thus interlacing it with the alternate and intermediate needles, and into the sinkers (not shown), which will prevent the elastic thread from rising. At the same time the knitting butts 3 of all the needles are lowered to the same level just before they engage the riser cam 8a of the conditioning cam mechanism. The drawing down of the selected raised alternate needles also restores their jacks to normal position, as clearly shown in Fig. 7.

After leaving the riser cam 8a the needles pass 15 along horizontally with their knitting butts in engagement with the upper edge of the cam ring 20, until they reach the shunt cam 12 (shown at the right in Fig. 7) when all of the needles are raised by the engagement of their 20 knitting butts with the shunt cam 12 to a level above that of the recessed portion of the riser cam 11, which carries all of them upwards into position to be engaged by the latch opener 19, which insures the opening of the remaining 25 needles, which did not receive the elastic thread.

As the needles are raised by the shunt cam 12 and riser cam 11 the elastic thread will be held by the sinkers and the needles will be raised high enough to carry the latches of those needles 30 which received the elastic thread in their hooks above the elastic thread. Thereupon the knitting butts of all of the needles engage the main knitting cam 5 and are drawn down in the usual knitting wave by that cam and the auxiliary 35 knitting cam 6, taking the body thread B in their hooks as they descend, and by reason of the interlacement of the elastic thread E with the needles, drawing stitch loops with alternate needles on opposite sides of the elastic thread,

40 the position of which is indicated by dotted lines in its relation to the needles in Fig. 7. This forms an elastic anti-ravel course. The portion of the needles adjacent to the point x of the cylinder on the right hand side of the gap G (Fig. 7) will now have stitch loops of body thread thereon, while the elastic thread will extend through all of said loops to form the anti-ravel, but it is necessary to continue the rotation of the cylinder substantially in an entire additional 45 revolution in order that the first course of knitting in this manner may be completed and the portion of the cylinder on the opposite side of gap G, indicated at y, shall be carried past the thread feed finger 17 for the elastic thread E, 50 and also the thread feed finger 16 for the body thread B. As a matter of fact, in order to insure the completion of the movement of the cylinder in each direction during its reciprocation, we construct the driving mechanism for the cylinder in such a manner as to produce a movement thereof in each direction through substantially two and a quarter revolutions before reversing.

55 In order to prevent the needles which have received both the elastic thread and body thread during the movement of the cylinder in one direction from being drawn down and raised by the knitting cam mechanism the second time they pass said cam mechanism, the shunt cam 12 (or 13) which has just been in operative position, is withdrawn and the auxiliary cam 6 (or 7) which has been in operative position, and the selector cam 14 (or 15) which has been in operative position, are also withdrawn, as shown in Fig. 8. This permits the knitting butts 3 of

all the needles to pass through the recessed portions of the riser cams 11 and 9 and past the auxiliary knitting cams 6 and 7 (see Fig. 8), no matter in which direction the cylinder is rotating, without operating the needles a second time, and as both of the selector cams are withdrawn the knitting butts of all the needles will pass under the conditioning cams 6a and 7a and be elevated by the adjacent riser cam 8a or 10a, without making a second needle selection, or feeding elastic thread E to the needles which have already received it. It will also be understood that after all of the needles have received the body thread B, and each needle has drawn a stitch, the latch openers cam perform no further useful function and they are therefore withdrawn to inoperative position and are not restored to operative position until the next top is set up on bare needles.

We prefer to provide the second course of the top, or in other words, the course which immediately follows the anti-ravel course, with the elastic thread, which in this and all subsequent courses in which it appears, is fed to selected needles, preferably spaced more widely than in the anti-ravel course, although this is not essential. In other words, the anti-ravel could be followed by a course of stitches not containing the elastic thread at all, and in the subsequent courses of the top in which the elastic thread is incorporated, it can be fed to selected needles having the same spacing as in the anti-ravel, or any desired spacing, if this is found desirable, it being understood however that by reason of the fact that the cylinder rotates first in one direction and then in the other, the separation of courses between any course containing elastic thread and the next following course containing elastic thread, must of necessity be an odd number of courses, that is to say, the elastic thread must be fed either in the next adjacent course to a previous course containing elastic thread, or in the third, fifth or seventh course thereafter. As hereinafter set forth, we prefer, after incorporating it in the course immediately following the anti-ravel course, to incorporate it in every third course of knitting.

It will be understood that in the second course of the top, or in other words, the course immediately following the anti-ravel, the cylinder will be rotated two and a quarter revolutions in a counter-clockwise direction (See Fig. 9), in which the direction of rotation is indicated by the arrow above the figure. The preceding revolution of the cylinder in the opposite direction, as in Fig. 7, will terminate with the gap G, carried beyond the feed mechanism for the elastic thread, at the left of Fig. 9. As the direction of rotation changes to counter-clockwise, the selector cam 15 is moved inwardly to an intermediate position in which it will engage only the long butts of the jacks, so as to raise every fourth needle, as indicated in Fig. 9, to receive the elastic thread E as the needles pass the thread feed finger 17 for the first time, in the manner previously described, the selected needles being drawn by the conditioning cams 5a and 7a to interlace the elastic thread between the selected needles and the intervening unselected needles, and place the elastic thread in control of the sinkers. At the same time the shunt cam 13 will be moved into operative position and the auxiliary knitting cam 7 is moved into operative position, so that all of the needles will be raised by the shunt cam 13 and riser cam 9 and carry the latches

of the selected needles above the elastic thread, and will receive the body thread as they pass the thread feed finger 16 the first time, each needle drawing a stitch of body thread through the loop of body thread thereon, which is cast off while the elastic thread which has been interlaced between the selected and unselected needles, as previously described, will pass over the hooks of the selected needles and be retained by the sinker loops of the stitches just formed. During the second passage of the needles past the thread feed fingers 17 and 16, the selector cam 15, the shunt cam 13 and auxiliary knitting cam 7, are withdrawn as previously described and as indicated in Fig. 8, so as to avoid feeding the elastic thread or body thread a second time to the needles during the second revolution of the cylinder.

In Fig. 13, which shows the inside of the fabric of the top, s represents the anti-ravel or selvage previously described and s' represents the immediately following course which also contains the elastic thread, united to the fabric by the sinker loops of every fourth stitch or wale as just described. It will also be understood that the elastic thread is continuous and that the portions in each course are connected by vertical floats, indicated at E', extending from each course containing the elastic thread to the next course containing it, as clearly indicated in Fig. 13, a vertical selvage indicated at S being formed at the opposite ends of the fabric. We prefer, in the knitting of the remaining part of the top, to incorporate the elastic thread in every third course, as shown, so that in the intermediate courses, indicated at a and b, a' and b', the body thread only will be knitted, the elastic thread being incorporated in courses c, c', etc., in the remaining portions of the top. In knitting the course indicated at a following the second course containing the elastic thread, which is indicated in Fig. 13 at s', the rotation of the cylinder is reversed and the course knitted exactly as described with reference to Fig. 7, except that both the selecting cams 14 and 15 remain in inoperative position, so that the needles receive only the body thread B from the thread feed finger 16 and draw loops through the stitches of the preceding course. Course b is knit in the same manner as indicated in Fig. 9, the direction of rotation of the cylinder being reversed and both selecting cams remaining in inoperative position, the shunt cam 12 being withdrawn and the shunt cam 13 being moved into operative position for knitting the main knitting thread B only on each of the needles throughout the courses a and b. It will also be understood that the elastic thread is fed under a desired degree of tension by any suitable tension means, and we have illustrated at 21 in the drawings, a suitable tension device comprising opposed discs, 21a, held together by a spring 21b adjustable by a nut 21c or other suitable means, whereby the desired tension may be imparted to the elastic thread during the knitting of the top.

Course c will be knit with the incorporation of the elastic thread, by moving the selector cam 14 only part way in, that is to say, into its intermediate position, where it engages only the long butts of the jacks so as to effect a 1 x 4 needle separation, the positions of the various cams being otherwise as shown in Fig. 7, and the course being knit by feeding the elastic thread E to the spaced selected needles, in this case every fourth needle, the selected needles

being drawn down by the conditioning cams 5a and 6a to interlace the elastic thread with the selected and unselected needles, and place the elastic thread in the control of the sinkers, after which the needles are carried around to the shunt cam 12 and raised to clear the recess in the riser cam 11. The needles are again further raised by cam 11 to carry the latches of the selected needles above the elastic thread, which is held in the sinkers. The needles are then drawn down the usual knitting wave by knitting cam 5 and auxiliary knitting cam 6, to take the body thread in their hooks and draw stitches through the stitch loops of the preceding course, the elastic thread passing over the latches and tops of the hooks of the selected needles and being united to the fabric by the sinker loops, as before described. As will be understood, the cylinder continues to revolve in the direction of the arrow in Fig. 7, to make substantially two and a quarter revolutions, the selecting cam 14, the shunt cam 12, and the auxiliary knitting cam 6, being withdrawn from operative position, so that the needles may pass the thread feed fingers 16 and 17 without taking either the body thread or the elastic thread the second time (see Fig. 8).

The knitting of the fabric in this manner continues for the desired number of courses and in each of the courses containing the elastic thread following the selvage course s, the float portions of the elastic thread, indicated at e, see Figs. 13 and 14, will form substantially continuous beads on the inner face of the fabric as previously stated.

After the last course containing the elastic thread, indicated at cx in Fig. 13, has been knit, we prefer to knit several courses, for example four courses d', d2, d3 and d4, of plain knitting without the elastic thread, followed by a transfer course f, of stitches of the body thread (see Fig. 13) in which the stitches are enlarged or elongated to facilitate transfer. The enlargement of the transfer stitches may be accomplished either by moving the sinkers inward to a greater extent during the formation of this special course or by increasing the length of the stitches by downward adjustment of the auxiliary knitting cam 6 or 7, or both. After the transfer course f is formed, we also prefer to knit a plurality of courses, preferably 12 to 16 courses of the body thread alone, portions of which are indicated at g', g2, g3 in Fig. 13, which are termed "raveling courses," which complete the top.

The top is then pressed off preferably by withdrawing the shunt cam 12 or 13 previously in operative position according to the direction of movement of the cylinder, so as to draw down the needles before they receive the body thread, and permitting the latches of all the needles to close, and enabling the needles to cast off the loops of the last knitted raveling course of plain knit fabric, so that the top will drop from the machine and be suspended within the cylinder by portions of the body thread B and elastic thread E between the last stitches containing the same, and the feed fingers therefor, and the machine will then be automatically placed in the condition shown in Fig. 7 to enable a new top to be set up on bare needles, and the operations previously described to be repeated in the sequence indicated.

This leaves the tops as they come from the machine in the form of flat pieces of plain knitting with the elastic thread incorporated therein,

as previously described, and extending transversely first in one direction and then in the other, the top having lateral, longitudinal selvages S formed at opposite sides of the gap G. The tops are then separated from each other by cutting the elastic thread close to the last stitch in which it occurs and severing the body thread, so as to leave an end which is available for unraveling the ravel courses g', g2, etc., back to the transfer course f after the transfer stitches thereof have been transferred to the needles of a full fashioned knitting machine. The leg of the stocking is knit integrally with the circular plain knit form fitting and self-supporting top. No binder or cutter is therefore required on the circular knitting machine and the thread feed fingers remain always in operative position.

It will be understood that the leg and foot of the stocking may be made on the same full fashioned machine, or the leg may be knit on one full fashioned machine and then transferred to a full fashioned footer on which the foot is knit. In either case the completed stocking will be like that shown in Figs. 14 and 15 in which T represents the circular plain knit form fitting top, L the full fashioned leg and F the full fashioned foot. The stocking is completed, as shown in Fig. 15, by uniting the edges of the stocking fabric in the usual manner, to form the seam S' extending down the back of the top T of the leg, the leg L, the heel portion along the bottom of the foot to the toe in the usual manner, the portion of the same at its upper end, indicated at S2 uniting the longitudinal selvage edges S of the top T. It will be noted, with reference to Fig. 14 that the elastic thread E is continuous throughout all the courses in which it occurs and is connected from one course to the next course in which it occurs at or adjacent to opposite edges of the selvage of the fabric, and is united to the fabric to form the longitudinal floats, indicated at e in Figs. 13 and 14.

Having described the needle and thread controlling elements of the machine, we will now describe the apparatus by which these elements are controlled automatically from suitable pattern mechanism, by reference to Figs. 1 to 6 inclusive. In these figures, see particularly Fig. 5, the cam 5 of the main knitting cam mechanism is shown supported by a bracket 5x on the cam plate, and the auxiliary knitting cams 6 and 7 are supported by horizontal slides 22 and 23 respectively, secured to the cam block by screws engaging slots 22a and 23a in said slides so that the auxiliary cams may be moved alternately into and out of operative relation with the knitting butts 3 of the needles. At the side of the top plate of the machine, indicated at 24, there is mounted a tubular shaft 25 in suitable bearings. This shaft 25 is provided centrally with a crank 26 connected by a link 27 with one end of a lever 28, the other end of which is connected by link 29 with the slide 22 for the auxiliary cam 6. The tubular shaft 25 is also provided with an actuating arm 30 connected with one end of a lever 31 pivoted to the main frame at its opposite end and provided with a lug 32 for engaging a cam track 33 on a rotating cam wheel 34, operated under the control of the pattern mechanism of the machine, for throwing the auxiliary cam 6 into and out of operative relation to the needle butts at the proper times, as previously described.

The auxiliary knitting cam 7 is in like manner operated by a shaft 35 which conveniently ex-

tends through the tubular shaft 25, and is provided at one end with a crank 36 connected by a link 37 with a centrally pivoted lever 38, pivoted to the frame of the machine, the other end of said lever being connected by link 39 with the slide 23 carrying the other auxiliary knitting cam 7.

The opposite end of the shaft 35 is provided with an arm 40 connected by a link with the outer end of a lever 41, pivoted at its opposite end to the main frame and lying parallel to the lever 31 and provided with a projection 42 for engaging a second cam track 43 of the cam wheel 34, for controlling the movements of the auxiliary cam 7 under the control of the pattern mechanism of the machine, the details of which need not be particularly described. Suitable springs 27a and 37a are shown in Fig. 5 connected respectively with the links 27 and 37 in such manner as to normally tend to force the auxiliary knitting cams into operative position so that the cam tracks 33 and 43 will act to withdraw the auxiliary cams 6 or 7 from normal position.

On the opposite side of the cylinder 1 from the knitting cams 5, 6 and 7, are located the conditioning cams 5a, 6a and 7a, which are supported by suitable brackets rigidly connected to the secondary cam block, see Fig. 5, as these cams always remain in the same positions throughout the operation of the machine, as previously indicated.

The shunt cams 12 and 13 are indicated on opposite sides of the cylinder in Fig. 5, each being supported by a horizontal slide mounted in a suitable guide, secured to the frame work of the machine. The shunt cam 12 is mounted on the slide 44, connected with its supporting guide 45 by a spring 46 normally tending to force the cam 12 into operative relation with the butts of the needle jacks. The slide 44 is connected by a link 47 with an arm 48 on a tubular shaft 49, see Figs. 3 and 5, the shaft 49 being broken away in Fig. 5 and the opposite end of the shaft 49 being illustrated at the right in Fig. 2. A shaft 59 extends through the hollow shaft 49 and is provided at one end with a crank 58 connected by a link 57 with one end of a lever 51a, the other end 57b of which engages a set screw 54a extending through a depending portion 54b of the slide 54, which carries the shunt cam 13, the slide 54 being mounted in a fixed guide 55 and provided with a spring 56 tending to move the shunt cam 13 into operative position while the lever arm 57b is operated to move the shunt cam 13 out of operative position. The tubular shaft 49 and the coaxial shaft 59 are operated in any desired way and in suitable timed relation under the control of the pattern mechanism.

In this instance we have shown a shaft 60 (see Fig. 2) with two rotary cams 61 and 62 which operate two vertically disposed levers 63 and 64 pivoted at their lower ends to the frame of the machine, one of said levers 64 being connected by a link 65 with a crank 66 on the shaft 49 and the other of said levers 63 being connected by a similar link 67 with a similar crank 68 on the shaft 59. The lever 64 and the link 65 are shown broken away in order that the lever 63 and link 67 beyond may be seen in Fig. 2. Each of the levers 63, 64 is provided with suitable springs 63a, 64a, to hold the connected lever in operative engagement with its respective cam 61 or 62.

Fig. 6 shows the location of the selecting cams 75

14 and 15 which, as indicated in Fig. 7, are located below and on opposite sides of the conditioning cams 6a and 7a. The selecting cam 14 is carried by a radial slide 70, mounted in a suitable guide 71, provided with a spring 72, normally tending to move the cam into operative position with respect to the needle selecting jacks. The outer end of the slide 70 is connected to one end of a bell crank lever 73 pivotally secured to the machine frame, the other end being connected by a link 74 with a crank 75 (see Fig. 5), on a shaft 76 extending through a tubular shaft 86 and provided at its opposite end with a crank 77, connected by a link 78 with an actuating lever 79, the opposite end of which is provided with a cam engaging portion, 79a.

The cam 15 is carried by a slide 80 supported in a bracket 81 secured to the frame of the machine and provided with a spring 82, normally tending to move the cam 15 into operative position with the butts of the needle selecting jacks. The outer end of the slide 80 is operatively connected with a lever 83 pivoted at one end to the frame and having its outer end connected by a link 84 (see Fig. 5) with a crank 85 at one end of the tubular shaft 86, the other end of which is provided with a crank 87 connected by link 88 with one end of a lever 89 mounted on the same pivot 79b as the lever 79, and provided at its outer end with a cam engaging portion 89a in vertical alignment with the cam engaging portion 79b of the lever 79.

The levers 79 and 89 are actuated by means of a plurality of cams 91, 92, 93 and 94 on a rotary sleeve 90, supported by a stationary post 95, supported on the framework of the machine, see Figs. 1, 2, 4 and 5. The sleeve 90 is provided at its lower end with a ratchet wheel 96 below which is an oscillating ratchet plate 97 provided at one end with a main pawl 98, below which is an auxiliary pawl 99, both pawls normally being held in engagement with the ratchet tooth of the ratchet wheel 96 by a suitable spring. The ratchet plate 97 is oscillated by means of a link 100, best shown in Fig. 2, which connects one end of the plate 97 with the upper end of a lever 101, the lower end of which is pivoted to a bracket 102 secured to the frame of the machine. The lever 101 is provided with a projection 103 adapted to be engaged by four anti-friction rollers or studs 104, located at equal distances apart around a gear wheel 105, which meshes with a driving pinion 106 on the main driving shaft 107 of the machine. The lower half of the ratchet wheel 96 has one of its teeth cut away at the lower portion, as indicated at 99a (see Fig. 2) in alignment with the lower pawl 99 and below the main actuating pawl 98. We provide means for throwing the main actuating pawl 98 out of operative position at a predetermined point, which is represented by the engagement of the pawl 99 with the tooth which is cut away at 99a. To this end we provide a cam 108 on the pattern shaft 109 of the machine, which operatively engages a lever 110 connected by a link 111 with a bellcrank 112 carrying a pin 113 at its upper end in position to engage a vertical pin 98a, see Figs. 2, 4 and 5, on an arm 98b of the pawl 98 on the opposite side of the pivotal support thereof from the part which engages the ratchet wheel. When the lever 110 engages the low portion of the cam 108, the pawl 98 will be disengaged from the ratchet wheel and the rotation of the sleeve 90 and the cams carried thereby will cease.

In order to insure that the sleeve 90 and its cams will always be brought to rest at the same point even if the pawl 98 should stick or otherwise become inoperative, the auxiliary pawl 99 is provided, and in such case the continued rotation of the sleeve will be accomplished by the pawl 99 until it falls into the space 99a formed by cutting away a tooth, and further rotary movements of the sleeve will then be prevented.

By reference to Fig. 2 it will be noted that the levers 89 and 79 are in position to engage respectively the rotary cams 91 and 93, being spaced by the engagement of suitable hubs, as shown. The hub of the lever 79 is rigidly connected with the pivot shaft 79b, the hub of the lever 89 being loose on the shaft and held in engagement therewith by a spring 79c (see Figs. 2 and 5). The pivot shaft 79 is supported in brackets secured to the main frame in such a manner that the shaft can move vertically and the upper end of the pivot shaft 79 carries a disc 114 (see Figs. 2 and 4) secured to the pivot shaft 79b and provided with an annular groove, which is engaged by inwardly extending projections on a yoke 115 at one end of a lever 116 (see Fig. 2) pivoted to a suitable bracket and connected by a link 117 with an arm 118 pivoted on the same axis 110a of the lever 110 and having a cam engaging portion to engage a rotary cam 119 on a cam wheel on the main pattern shaft 109. It will be seen that when the cam engaging portion of the lever 118 engages the low portion 119a of the cam 119, the rod 117 will rise and depress the yoke 115, thereby depressing the levers 89 and 79 into engagement respectively with the cam wheels or discs 92 and 94.

As previously described, the lever 89 controls the selecting cam 15, while the lever 79 controls the selecting cam 14. It follows from this construction that in starting up on bare needles to knit the anti-ravel or selvage, as before described, the levers 89 and 79 will engage respectively the cam discs 91 and 93, as shown in Fig. 2. These cams are constructed so that on the first movement of the cylinder in the clockwise direction to set up on bare needles, portion 79a of the lever 79 will enter a recess 93a, indicated in dotted lines in Fig. 1, releasing the selecting cam 14, which will be forced inwardly into the gap G and far enough to engage both the long and short butts of the selecting jacks, so that as the cylinder is revolved in clockwise direction, as before described, all of the jacks representing every other needle, will be raised to receive the elastic thread to be subsequently interlaced between adjacent needles, and the revolution of the cylinder will continue for two and a quarter revolutions, as before described, during a portion of which all the needles will take the body thread and form the anti-ravel. When the first course is completed it will be understood that the gap G will be in alignment with the selecting cam 15, so that as the rotation of the cylinder is reversed, the portion 89a of the lever 89 will drop into the recessed portion 91a of the cam wheel 91, and bring the selecting cam 15 into position to engage only the long butts of the selecting jacks, it being limited in its inward movement by the connections between the lever 89 and the cam 15, so that it cannot under any circumstances engage the short butts. The cylinder then makes two and a quarter revolutions, selecting during one revolution every fourth needle by means of the cam 15, to receive the elastic thread, and feeding body thread to all of the needles, as before de-

scribed, the revolution of the cylinder in the reverse or counter clockwise direction also terminating with the gap G, in alignment with the selecting cam 14.

It will be understood that the revolution of the cylinder in each direction terminates with the gap in alignment with one or other of the selecting cams, so that when either of said cams is to be moved into operative position, it will not interfere with or cause breakage of the butts of any of the selecting jacks, and to that end the selecting cams will be of less horizontal width than the gap. Before the first course, composed entirely of body thread is knit, the low portion 119a of the cam 119 will effect the raising of the rod 117 and the spring 79c will depress the levers 89 and 79 into operative relation with the cam discs 92 and 94 respectively. These discs are provided with recesses 92a and 94a, indicated in dotted lines in Fig. 4, and so arranged as to insure the formation of two intermediate courses, in this instance without permitting either of the selecting cams 14 or 15 to be moved into operative position, whereupon one or the other of said selecting cams will be brought into operative position, according to the direction of the rotary movement of the cylinder, and the selecting cams 14 and 15 will be controlled by the cam discs 92 and 94 during the remaining portion of the formation of that part of the top containing the elastic thread in courses spaced equally, and in this instance every third course.

It will be understood, however, that while in control of the cam discs 92 and 94, the selecting cam 14 will be moved inward only far enough to engage the long butts of the selecting jacks, and in this instance we provide lockout mechanism for preventing the cam 14 from moving into the full extent to which it is moved in the setting up course. This lockout mechanism comprises a lockout pin 120, which depends from the bell-crank 73 by which the slide 78 of the cam 14 is permitted to move inwardly, the said pin being engaged by one end of a lockout lever 121 (see Figs. 1, 3, 4 and 6), said knockout lever being connected with a vertically movable bar 122, the lower end of which is slotted at 122a to engage a pin 123 in the end of the pattern drum shaft (see Fig. 3). This bar 122 is provided with a friction roller 124 adapted to engage a cam projection 125 on a drum 126 mounted on the pattern shaft. The bar 122 is provided with a spring 127, in this instance connected to a stud on the bar end to the guiding stud 123, normally tending to draw the bar 122 downward and hold it in operative engagement with the lockout pin 120. This cam projection 125 or lug will be brought into engagement with the friction roller 124 during the time that the anti-ravel course is being formed and immediately thereafter the friction roller 124 will pass off of the projection or lug 125, permitting the spring 127 to raise the lockout lever 121 into position with respect to the pin to limit the inward movement of the cam 14 whenever it is released by its control mechanism during the knitting of the other elastic incorporated courses of the top.

After the completion of all the courses containing the elastic thread, the rotation of the sleeve 90 and its associated cam discs will be discontinued, as before stated, at the point in the revolution of the sleeve 90 where the auxiliary pawl 99 engages the space 99a in the ratchet wheel 96. This will permit the knitting of the courses d', d2, d3 and d4, as previously described,

with the body thread only, and without any introduction of the elastic thread. Obviously under these circumstances the lever 89 and 79 will not be actuated. In order to preclude any possibility of these levers being moved during the plain knit courses, we prefer to provide a secondary lockout mechanism for the levers 89 and 79. This mechanism comprises a bellcrank lever 128 (see Fig. 5) having an upwardly extending arm 129, which is thrown laterally into position to engage both the levers 89 and 79 and hold them in their inoperative positions, the said bellcrank being operated by a vertically disposed rod 130 (see Fig. 3) connected at its upper end with the bellcrank lever 128 and at its lower end to a lever 131 pivoted to the frame and having a cam engaging portion for engaging a cam 132 on the pattern shaft of the machine. The lever 131 is shown provided with a spring 131a for holding it in operative relation with the cam.

We also provide means for automatically increasing the size of the stitch of body thread, indicated at *f* in Fig. 13, in the transfer course of stitches following the formation of the stitches *d'*, *d2*, *d3* and *d4*. The increase in the size of the stitch may be produced by increasing the throw of the sinkers or by increasing the length of the stitch by varying the position of the draw-down cams, or both. In the drawings we have shown mechanism for accomplishing both of these results. For lengthening the stitch, the cam block or cam ring is supported upon a vertically movable plate, indicated at 133, supported on a vertical slide 134, which may be bodily raised or lowered by means of a cam 135 on the pattern cam shaft of the machine. Independent vertical adjustment of the cam block is accomplished by means of a set screw 136 in the usual way.

The sinkers are not shown in detail in the drawings, but it will be understood that they will be of usual construction, and in Fig. 4 there is shown a horizontally movable pivoted sinker cam 137, so disposed as to increase the inward movement of the sinkers and cause them to draw longer stitches during the knitting of the transfer course. In this instance the lever 137 is provided with a pin 138, which is engaged by one end of a pivoted lever 139 operatively connected with a bellcrank 140, one arm of which is connected by a vertical rod 141 with a lever 142, having a cam engaging portion which engages a cam projection 143 on a cam disc mounted on the pattern shaft 109. This cam projection 143 is of very short peripheral extent, and will simply actuate the lever 139 and cam 137 to increase the inward throw of the sinkers during the single revolution when the transfer course *f* (Fig. 13) is knit, after which the plate carrying the cam block and the sinkers will resume their normal operation during the knitting of the raveling courses *g'*, *g2*, *g3* etc.

In the description of the operation of the machine, the operation of the latch openers during the setting up course to produce the anti-ravel was described. Obviously after the needles have all drawn stitches, there will be no further necessity for the latch openers, and after the formation of the anti-ravel, they are automatically moved out of operative position. As shown, for example in Fig. 4, each of the latch openers is carried by a bellcrank lever. The latch opener 19 is carried by one arm of a bellcrank lever 144 and held in operative position by a spring 145, while the latch opener 18 for the elastic 75 gap, so that the cams 12, 13, and 14, 15 can be

thread is carried by one arm of a bellcrank lever 146 and held normally in operative position by a spring 147. The pattern cam shaft 109 is provided with a control cam for the latch openers, indicated at 148, which actuates a lever 149 pivoted coaxially with the levers 142 and 131, the said lever 149 carrying at one end a vertical rod 150, the upper end of which is connected with a bellcrank lever 151, having a vertical arm connected by link 152 with the bellcrank 144 for actuating the latch opener 19. The other end of lever 149 is connected by a vertical rod, 153, indicated in dotted lines in Fig. 3, and shown in full lines in Fig. 1, the upper end of which is connected with a lever 154, which in turn is connected by a link 155 with a bellcrank lever 156, having a vertical arm in position to engage the bellcrank 146 and move the latch opener 18 out of operative position. By this means the latch openers are simultaneously moved into inoperative position as soon as the anti-ravel is completed.

We also preferably provide a second means for automatically pressing off the top, at the conclusion of the raveling courses *g'*, *g2*, etc., by lifting the feed finger 16 for the body thread out of operative position, in a well known way. In the present instance (see Fig. 1 for example) the thread feed finger 16 is indicated at the upper part of the figure, pivotally mounted at 16a and provided with a projection 16b, engaged by the usual spring 16c. Beneath this finger is provided a pivoted lever 157, pivoted between its ends in the adjacent bracket secured to the frame of the machine, having its inner end in engagement with the finger 16, and its outer end connected by a vertical rod 158 with a lever 159, engaging a cam 160 on the main pattern shaft 109, so that after the raveling courses have been completed, the lever 157 will raise the feed finger 16 while the cylinder is in motion, following the last raveling course and thus preventing the feed of body thread to the needles, whereupon the needles will cast off their stitches and the completed circular plain knit elastic incorporated top, constructed as previously described, will be freed from the machine and be supported only by the elastic thread *E* and body thread *B*, leaving the machine free for the starting of another top by setting up on bare needles and forming an anti-ravel in the manner previously described.

It will be understood that the presence of the gap *G* in the needle series facilitates the movement of the movable selecting cams 14 and 15 and shunt cams 12 and 13 radially into operative position so as to act upon the first needle at one or the other side of the gap, according to the direction of rotation of the cylinder. As previously stated, the cylinder will be rotated in each direction to such an extent, in this instance two and a quarter revolutions, as to carry all the needles past the thread feed finger 17 for the elastic thread, after which the selecting cam 15 is withdrawn, then past the feed finger 16 for the inelastic thread, after which the shunt cam 12 in operation is withdrawn, sufficiently further to come to rest with the gap *G* into alignment with the other selecting cam before reversing. It will also be understood that during the first rotation in each direction, whether elastic thread has been fed to the selected needles or not, one or other of the shunt cams is moved inwardly into operative position, when in alignment with the 75 gap, so that the cams 12, 13, and 14, 15 can be

moved into operative position without danger of injury to the needle butts or the butts of the selecting jacks.

What we claim and desire to secure by Letters Patent is:

1. In a circular knitting machine, the combination of a knitting cylinder, a series of consecutive independently operable needles extending less than completely around the cylinder and forming a gap, knitting cam mechanism, selecting cam mechanism, means for establishing reciprocating relative rotary movement between said cylinder and cam mechanisms, means for feeding a continuous elastic thread to spaced selected needles during the rotation of the cylinder in both directions, and means for feeding an inelastic thread to all the needles.

2. In a circular knitting machine, the combination of a knitting cylinder, a series of consecutive independently operable needles extending less than completely around the cylinder, and forming a gap, knitting cam mechanism, selecting cam mechanism, means for establishing reciprocating relative rotary movement between said cylinder and cam mechanisms, means for feeding a continuous elastic thread to spaced selected needles during the rotation of the cylinder in both directions, means for feeding an inelastic thread to all of the needles during the rotation of the cylinder in both directions, and means for discontinuing the feed of elastic thread during certain rotary movements of the cylinder and at one or other end of the series of consecutive needles while continuing the feed of inelastic thread to all the needles, to form a course, or courses, composed entirely of inelastic thread between, and spacing the courses containing elastic thread.

3. In a circular knitting machine, the combination of a knitting cylinder, a series of consecutive independently operable needles extending less than completely around said cylinder and forming a gap, said needles being provided with knitting butts, means for rotating the cylinder alternately in opposite directions, knitting cam mechanism for engaging said knitting butts and operating the needles in both directions of rotation of the cylinder, means for feeding an inelastic thread to all the needles, selecting means for raising spaced selected needles, in advance of the knitting cam mechanism in both directions of rotation of the cylinder, means for feeding a continuous elastic thread to the selected needles, and means for throwing the selecting means out of operation at intervals to effect the knitting of one or more courses composed of inelastic thread only between adjacent courses containing the elastic thread and to float the elastic thread vertically at one or other edge of the fabric.

4. In a circular knitting machine, the combination of a knitting cylinder, a series of consecutive independently operable needles extending less than completely around said cylinder and forming a gap, said needles being provided with knitting butts, means for rotating the cylinder alternately in opposite directions, knitting cam mechanism for engaging said knitting butts and operating the needles in both directions of rotation of the cylinder, means for feeding an inelastic thread to all the needles, selecting means for raising spaced selected needles, in advance of the knitting cam mechanism in both directions of rotation of the cylinder, comprising selecting jacks for certain of said needles,

provided with butts, oppositely disposed selecting cams for engaging the butts of said selecting jacks, and pattern controlled mechanism for bringing one or other of said selecting cams into operative position, and for maintaining both selecting cams out of operative position, and means for feeding a continuous elastic thread to the selected needles.

5. In a circular knitting machine, the combination of a knitting cylinder, a series of consecutive independently operable needles extending less than completely around said cylinder and forming a gap, said needles being provided with knitting butts, means for rotating the cylinder alternately in opposite directions, knitting cam mechanism for engaging said knitting butts and operating the needles in both directions of rotation of the cylinder, means for feeding an inelastic thread to all the needles, selecting means for raising spaced selected needles, in advance of the knitting cam mechanism in both directions of rotation of the cylinder, comprising selecting jacks for alternate needles, certain of said jacks being provided with long butts and others with short butts, a thread feed finger for feeding elastic thread to selected needles, selecting cams on opposite sides of a vertical line passing through said feed finger, mechanism for moving one of said selecting cams into position to engage all of the butts of the selecting jacks, to raise alternate needles into position to take the elastic thread on bare needles to form an anti-ravel, and for alternately moving one or other of said selecting cams into operative position to engage the long butts only of said jacks, to raise more widely spaced needles into position to receive the elastic thread according to the direction of rotation of the cylinder.

6. In a circular knitting machine, the combination of a knitting cylinder, a series of consecutive independently operable needles extending less than completely around said cylinder and forming a gap, said needles being provided with knitting butts, means for rotating the cylinder alternately in opposite directions, knitting cam mechanism for engaging said knitting butts and operating the needles in both directions of rotation of the cylinder, means for feeding an inelastic thread to all the needles, selecting means for raising spaced selected needles, in advance of the knitting cam mechanism in both directions of rotation of the cylinder, comprising selecting jacks for certain needles provided with selecting butts, a thread feed finger for feeding an elastic thread to selected needles, selecting cams on opposite sides of a vertical line passing through said feed finger and movable into and out of position to engage the butts of the jacks of selected needles and raise said needles into position to take the elastic thread, conditioning cam mechanism located between the selecting cams and in position to engage the knitting butts of the needles, and comprising cams for drawing down the unselected needles before they receive elastic thread, and cams for drawing down the selected needles after they have received the elastic thread, to bring all of the needles to a common level with the elastic thread and interlace it with the selected and unselected needles.

7. In a circular knitting machine, the combination of a knitting cylinder, a series of consecutive independently operable needles extending less than completely around said cylinder and forming a gap, said needles being provided with knitting butts, means for rotating the cyl-

nder alternately in opposite directions, knitting cam mechanism for engaging said knitting butts and operating the needles in both directions of rotation of the cylinder, means for feeding an inelastic thread to all the needles, selecting means for raising spaced selected needles, in advance of the knitting cam mechanism in both directions of rotation of the cylinder, comprising selecting jacks for certain needles, provided with selecting butts, a thread feed finger for feeding an elastic thread to selected needles, selecting cams on opposite sides of a vertical line passing through said feed finger and movable into and out of position to engage the butts of the jacks of selected needles and raise said needles into position to take the elastic thread, conditioning cam mechanism located between the selecting cams and in position to engage the knitting butts of the needles, and comprising a central cam for drawing down the selected needles, and auxiliary cams on opposite sides of the central cam for drawing down the unselected needles on one side of the central cam and continuing to draw down the selected needles on the other side of the selecting cam, to bring all of the needles to the same level and carry the elastic thread into position to be engaged by the sinkers and interlace the elastic thread between the selected and unselected needles during the rotation of the cylinder in either direction when one or other of the selecting cams is in operative position.

8. In a circular knitting machine, the combination of a knitting cylinder, a series of consecutive independently operable needles extending less than completely around said cylinder and forming a gap, said needles being provided with knitting butts, means for rotating the cylinder alternately in opposite directions, needle selecting mechanism for placing selected needles in thread feeding position, means for feeding an elastic thread to the selected needles only, a thread feed finger for feeding inelastic thread to all of the needles, main knitting cam mechanism for engaging the knitting butts of the needles and comprising a main knitting cam, auxiliary knitting cams on opposite sides of the main knitting cam and movable into and out of operative position, and pattern control mechanism for moving one or other of said auxiliary knitting cams into operative position according to the direction of rotation of the cylinder to cause each of the needles to draw a stitch of inelastic thread and for maintaining both of said auxiliary knitting cams in inoperative position to prevent the feeding of inelastic thread to the needles thereafter in the further rotary movement of the cylinder in the same direction.

9. In a circular knitting machine, the combination of a knitting cylinder, a series of consecutive independently operable needles extending less than completely around said cylinder and forming a gap, said needles being provided with knitting butts, means for rotating the cylinder alternately in opposite directions, needle selecting mechanism for placing selected needles in thread feeding position, means for feeding an elastic thread to the selected needles only, a thread feed finger for feeding inelastic thread to all of the needles, main knitting cam mechanism for engaging the knitting butts of the needles comprising a main knitting cam, auxiliary knitting cams on opposite sides of the main knitting cam movable into and out of operative position, oppositely disposed riser cams on opposite sides

5 of the main knitting cam and auxiliary knitting cams provided each with a recess in horizontal alignment with the auxiliary knitting cams for the passage of needle butts therethrough, and shunt cams on opposite sides of the knitting cams and riser cams, movable into and out of operative position and disposed in horizontal alignment with the recesses in said riser cams, and pattern control mechanism for moving the shunt cams in advance of the knitting cams and riser cams into operative position to raise the needle butts into position to engage the adjacent riser cam and for simultaneously moving the auxiliary knitting cam on the opposite side of the main knitting cam into operative position to cause all the needles to take the inelastic thread and draw stitches, and for withdrawing said previously actuated shunt cam and auxiliary knitting cam to permit the needle butts to pass through the recesses of both riser cams without taking the elastic thread thereafter during the continuous movement of the cylinder in the same direction.

10. In a circular knitting machine, the combination of a knitting cylinder, a series of consecutive independently operable needles extending less than completely around said cylinder and forming a gap, said needles being provided with knitting butts, means for rotating the cylinder alternately in opposite directions, needle selecting mechanism for placing selected needles in thread feeding position, means for feeding an elastic thread to the selected needles only, conditioning cam mechanism for engaging the butts of the needles to draw down the selected needles 25 to bring all the needles to the same level and interlace the elastic thread with the selected and unselected needles, a thread feed finger for feeding inelastic thread to all the needles, knitting cam mechanism comprising a stationary main knitting cam, auxiliary knitting cams below and on opposite sides of the main knitting cam and movable into and out of operative position, and riser cams on opposite sides of the knitting cams, and provided with recesses in horizontal alignment with the auxiliary knitting cams, shunt cams on opposite sides of the knitting cam mechanism movable into and out of operative position and arranged in horizontal alignment with the recesses in said riser cams, pattern controlled mechanism for moving one of said shunt cams and one of said auxiliary knitting cams into operative position to enable the shunt cam and adjacent riser cam to elevate the needles to carry the latches of the selected needles above the elastic thread carried thereby and to enable all of the needles to take the inelastic thread and draw stitches by means of the main knitting cam and auxiliary knitting cam, to unite the elastic thread to the fabric at the stitches of inelastic thread drawn by the selected needles, said pattern mechanism being constructed to withdraw the previously actuated shunt cam and auxiliary knitting cam from operative position, to permit the needle butts to pass through the recesses in the riser cams and bypass the knitting cams after all of the needles have drawn stitches of inelastic thread during the continued movement of the cylinder in the direction.

11. In a circular knitting machine, the combination of a rotary knitting cylinder, a series of consecutive independently operable needles extending less than completely around said cylinder and forming a gap, said needles being provided with knitting butts and certain of said needles being provided with selecting jacks, select-

ing cams for engaging the butts of said selecting jacks to raise said selected needles into thread receiving position, means for feeding an elastic thread under tension to said selected needles, drawdown cam mechanism for engaging the needle butts to bring said needles to the same level and interlace the elastic thread with the selected and unselected needles, knitting cam mechanism, comprising a main knitting cam and auxiliary knitting cams located on opposite sides and below the main knitting cam and movable into and out of operative position, riser cams on opposite sides of the auxiliary knitting cams provided with recessed portions in horizontal alignment therewith, shunt cams on opposite sides of the riser cams in alignment with the recesses therein, pattern controlled mechanism for moving one of said riser cams into and out of operative position, pattern controlled mechanism for moving one of said selecting cams into operative position in advance of the elastic thread feeding means and for moving the shunt cam in advance of the knitting cam mechanism and the auxiliary knitting cam on the opposite side of the main knitting cam into operative position and raise all the needles, and to carry the latches of the selected needles above the elastic thread carried thereby, and place them in position to receive the inelastic thread, means for feeding the inelastic thread to the needles to enable each needle to draw a loop of elastic thread and cause stitches drawn by the selected needles to unite the elastic thread to the fabric, said pattern controlled mechanism being constructed to withdraw the previously actuated selecting cam after all the needles have passed the feed mechanism for the elastic thread and to withdraw said previously actuated shunt cam and auxiliary knitting cam after all of the needles have taken the inelastic thread, to permit the needles thereof to pass the feeding mechanism for the elastic thread and the inelastic thread, without taking the same during continued movement of the cylinder in the same direction.

12. In a circular knitting machine, the combination of a knitting cylinder, a series of consecutive independently operable needles extending less than completely around said cylinder and forming a gap, said needles being provided with knitting butts, means for rotating the cylinder alternately in opposite directions through more than a complete revolution, a thread feed finger for feeding an elastic thread to selected needles, a tension means for said elastic thread, selecting jacks for alternate needles, certain of said jacks for more widely spaced selected needles being provided with long butts, and the other of said jacks being provided with short butts, a selecting cam movable when the cylinder is rotating in one direction, into position to engage all the butts of said jacks, and into an intermediate position to engage the long butts only, an oppositely disposed selecting cam movable into position to engage the long butts only during the reverse rotation of the cylinder, a latch opener located in advance of the elastic thread feed for opening the latches of the selected alternate needles in setting up on bare needles, conditioning cam mechanism for bringing the needles to the same level and interlacing the elastic thread with the selected and unselected needles, means for feeding an inelastic thread to all of the needles, a latch opener in advance of the said means for opening the latches of the unselected alternate needles in setting up on bare needles, means for raising all of the nee-

dles to carry the latches of the selected needles above the elastic thread, and stitch forming mechanism for drawing loops on all the needles alternately on opposite sides of the elastic thread, 5 to form an anti-ravel when the cylinder is rotating in one direction, pattern controlled mechanism for moving the previously operated selecting cam out of operative position and the other selecting cam into operative position with 10 respect to the long butts only of the selecting jacks when the direction of rotation of the cylinder is reversed immediately following the formation of the anti-ravel, to raise the more widely separated selected needles to receive the elastic 15 thread and be drawn down by the conditioning cam mechanism to the level of the unselected needles, and interlace the elastic thread between the selected and unselected needles, pattern controlled mechanism for adjusting the stitch forming 20 mechanism to enable all the needles to take the inelastic thread, and means for throwing the latch openers out of operation during the said reverse rotation and subsequent rotations of the cylinder.

13. In a circular knitting machine, the combination of a knitting cylinder, a series of consecutive independently operable needles extending less than completely around said cylinder and forming a gap, said needles being provided with knitting butts, means for rotating the cylinder alternately in opposite directions, means for feeding an elastic thread under tension to selected needles, oppositely disposed selecting 30 cams for raising selected needles in advance of the elastic thread feed mechanism in both directions of revolution of the cylinder, cam mechanism for drawing down the selected needles to the level of the unselected needles and interlacing the elastic thread therewith, means for feeding an inelastic thread, knitting cam mechanism including a main knitting cam and oppositely disposed auxiliary knitting cams movable into and out of operative position, oppositely disposed riser cams provided with recesses in horizontal alignment with the auxiliary knitting cams, shunt 35 cams on opposite sides of the riser cams movable into and out of operative position, pattern controlled mechanism for the selecting cams, the auxiliary knitting cams and shunt cams, constructed to maintain both of the selecting cams in inoperative position to enable the machine to knit a course or courses of inelastic stitches only between courses containing the elastic thread.

14. In a circular knitting machine, the combination of a knitting cylinder, a series of consecutive independently operable needles extending less than completely around said cylinder and forming a gap, said needles being provided with knitting butts, means for rotating the cylinder alternately in opposite directions, means for feeding an elastic thread under tension to selected needles, oppositely disposed selecting cams for raising selected needles in advance of the elastic 40 thread feed mechanism in both directions of revolution of the cylinder, cam mechanism for drawing down the selected needles to the level of the unselected needles and interlacing the elastic thread therewith, means for feeding an inelastic thread, knitting cam mechanism including a main knitting cam and oppositely disposed auxiliary knitting cams movable into and out of operative position, oppositely disposed riser cams provided with recesses in horizontal alignment with the auxiliary knitting cams, shunt 45 cams on opposite sides of the riser cams movable into and out of operative position, pattern controlled mechanism for the selecting cams, the auxiliary knitting cams and shunt cams, constructed to maintain both of the selecting cams in inoperative position to enable the machine to knit a course or courses of inelastic stitches only between courses containing the elastic thread.

15. In a circular knitting machine, the combination of a knitting cylinder, a series of consecutive independently operable needles extending less than completely around said cylinder and forming a gap, said needles being provided with knitting butts, means for rotating the cylinder alternately in opposite directions, means for feeding an elastic thread under tension to selected needles, oppositely disposed selecting cams for raising selected needles in advance of the elastic 50 thread feed mechanism in both directions of revolution of the cylinder, cam mechanism for drawing down the selected needles to the level of the unselected needles and interlacing the elastic thread therewith, means for feeding an inelastic thread, knitting cam mechanism including a main knitting cam and oppositely disposed auxiliary knitting cams movable into and out of operative position, oppositely disposed riser cams provided with recesses in horizontal alignment with the auxiliary knitting cams, shunt 55 cams on opposite sides of the riser cams movable into and out of operative position, pattern controlled mechanism for the selecting cams, the auxiliary knitting cams and shunt cams, constructed to maintain both of the selecting cams in inoperative position to enable the machine to knit a course or courses of inelastic stitches only between courses containing the elastic thread.

16. In a circular knitting machine, the combination of a knitting cylinder, a series of consecutive independently operable needles extending less than completely around said cylinder and forming a gap, said needles being provided with knitting butts, means for rotating the cylinder alternately in opposite directions, means for feeding an elastic thread under tension to selected needles, oppositely disposed selecting cams for raising selected needles in advance of the elastic 60 thread feed mechanism in both directions of revolution of the cylinder, cam mechanism for drawing down the selected needles to the level of the unselected needles and interlacing the elastic thread therewith, means for feeding an inelastic thread, knitting cam mechanism including a main knitting cam and oppositely disposed auxiliary knitting cams movable into and out of operative position, oppositely disposed riser cams provided with recesses in horizontal alignment with the auxiliary knitting cams, shunt 65 cams on opposite sides of the riser cams movable into and out of operative position, pattern controlled mechanism for the selecting cams, the auxiliary knitting cams and shunt cams, constructed to maintain both of the selecting cams in inoperative position to enable the machine to knit a course or courses of inelastic stitches only between courses containing the elastic thread.

17. In a circular knitting machine, the combination of a knitting cylinder, a series of consecutive independently operable needles extending less than completely around said cylinder and forming a gap, said needles being provided with knitting butts, means for rotating the cylinder alternately in opposite directions, means for feeding an elastic thread under tension to selected needles, oppositely disposed selecting cams for raising selected needles in advance of the elastic 70 thread feed mechanism in both directions of revolution of the cylinder, cam mechanism for drawing down the selected needles to the level of the unselected needles and interlacing the elastic thread therewith, means for feeding an inelastic thread, knitting cam mechanism including a main knitting cam and oppositely disposed auxiliary knitting cams movable into and out of operative position, oppositely disposed riser cams provided with recesses in horizontal alignment with the auxiliary knitting cams, shunt 75 cams on opposite sides of the riser cams movable into and out of operative position, pattern controlled mechanism for the selecting cams, the auxiliary knitting cams and shunt cams, constructed to maintain both of the selecting cams in inoperative position to enable the machine to knit a course or courses of inelastic stitches only between courses containing the elastic thread.

cams on opposite sides of the riser cams movable into and out of operative position, pattern controlled mechanism for the selecting cams, the auxiliary knitting cams and shunt cams, constructed to maintain both of the selecting cams in inoperative position to enable the machine to knit a course or courses of inelastic stitches only between courses containing the elastic thread, and means for increasing the size of the stitches of inelastic thread only in a complete course of stitches to form a transfer course.

15. In a circular knitting machine, the combination of a knitting cylinder, a series of consecutive independently operable needles extending less than completely around said cylinder and forming a gap, said needles being provided with knitting butts, means for rotating the cylinder alternately in opposite directions, means for feeding an elastic thread under tension to selected needles, oppositely disposed selecting cams for raising selected needles in advance of the elastic thread feed mechanism in both directions of revolution of the cylinder, cam mechanism for drawing down the selected needles to the level of the unselected needles and interlacing the elastic thread therewith, means for feeding an inelastic thread, knitting cam mechanism including a main knitting cam and oppositely disposed auxiliary knitting cams movable into and out of operative position, oppositely disposed riser cams provided with recesses in horizontal alignment with the auxiliary knitting cams, shunt cams on opposite sides of the riser cams movable into and out of operative position, pattern controlled mechanism for the selecting cams, the auxiliary knitting cams and shunt cams, constructed to maintain both of the selecting cams in inoperative position to enable the machine to knit a course or courses of inelastic stitches only between courses containing the elastic thread, and pattern controlled mechanism for moving the thread feed mechanism for the inelastic thread out of operative position to automatically press off the fabric when completed.

16. In a circular knitting machine, the combination of a knitting cylinder, a series of consecutive independently operable needles extending less than completely around the cylinder and forming a gap, knitting cam mechanism, selecting cam mechanism including horizontally separated radially movable selecting cams of less width than said gap, means for feeding an elastic thread to spaced selected needles, means for feeding an inelastic thread to all of the needles, and means for establishing reciprocating relative rotary movement between the cylinder and said cam mechanisms of such extent in each direction as to carry all the needles of the series past both thread feeding means and place the gap in alignment with one or other of said selecting cams, to permit the movement thereof radially into operative position.

5 17. In a circular knitting machine, the combination with a knitting cylinder, a series of consecutive independently operable needles extending less than completely around said cylinder and forming a gap, said needles being provided with knitting butts, and certain of said needles being provided with selecting jacks having butts, knitting cam mechanism for engaging the knitting butts and operating the needles in both directions of rotation of the cylinder, means for feeding an inelastic thread to all the needles of the series, radially movable selecting cams of a width less than the width of said gap for engaging butts of the selecting jacks in advance of the knitting cam mechanism in both directions of rotation of the cylinder, means for feeding a continuous elastic thread to the selected needles, means for rotating the cylinder alternately in opposite directions to carry all of the needles past the elastic thread feeding means, and also the inelastic thread feeding means and sufficiently further to terminate said movement in each direction with the gap in radial alignment with one or other of the selecting cams.

20 18. In a circular knitting machine, the combination of a knitting cylinder, a series of consecutive independently operable needles extending less than completely around said cylinder and forming a gap, said needles being provided with knitting butts, means for rotating the cylinder alternately in opposite directions, knitting cam mechanism for engaging said knitting butts and operating the needles in both directions of rotation of the cylinder, means for feeding an inelastic thread to all the needles, selecting means for raising spaced selected needles, in advance of the knitting cam mechanism in both directions of rotation of the cylinder, means for feeding a continuous elastic thread to the selected needles, and means for throwing the selecting means out of operation at intervals to effect the knitting of one or more courses composed of inelastic thread only between adjacent courses containing the elastic thread and to float the elastic thread vertically at one or other edge of the fabric, said knitting cam mechanism being provided at each side thereof with a shunt cam for engaging the knitting butts of all the needles and moving them into position to operatively engage the knitting cam mechanism, and pattern controlled mechanism for moving one or other of said shunt cams into operative position in advance of the knitting cam mechanism at a point in the revolution of the cylinder when said gap is in radial alignment with said shunt cam and for withdrawing said shunt cam after a complete revolution of the cylinder in either direction thereof.
